UNITED STATES PATENT OFFICE.

JESSE H. BARTON, OF BROWNSVILLE, TENNESSEE.

SASH-LOCK.

No. 879,078.

Specification of Letters Patent.

Patented Feb. 11, 1908.

Application filed August 7, 1907. Serial No. 387,440.

To all whom it may concern:

Be it known that I, JESSE H. BARTON, a citizen of the United States, and a resident of Brownsville, in the county of Haywood and 5 State of Tennessee, have invented new and useful Improvements in Sash - Locks, of which the following is a full, clear, and exact description.

This invention has in view an improved 10 sash lock which is adapted to securely lock both sashes at any desired position within the window frame, and which operates to make the window proof against burglars in that the sashes cannot be unlocked after 15 breaking the glass by passing the hand through the window to the lock.

The invention further resides in certain 20 special features of construction and arrangement of parts which will be fully set forth hereinafter and particularly pointed out in the claims.

Reference is to be had to the accompanying 25 drawings forming a part of this specification, in which similar characters of reference indicate corresponding parts in all the views.

Figure 1 is an inside elevation of a window with my improved sash lock applied thereto, the latter being shown in locked position; Fig. 2 is a fragmentary view of the window 30 on an enlarged scale, at the point at which the lock is applied; Fig. 3 is a sectional plan view on the line 3—3 of Fig. 2; Fig. 4 is a perspective view of the cam and operating-lever detached, which form elements of the sash lock, 35 and Fig. 5 is a view similar to Fig. 2, showing the position of the cam and lever when the sashes are unlocked.

In order to disclose the manner in which I 40 contemplate applying my improved sash lock, I have shown an ordinary window consisting of a frame 10 having the upper and lower sashes 11 and 12, respectively, slidably therein and separated at opposite sides by parting beads 13.

The sash lock consists of a bracket 14 45 which is attached at one side and to the upper edge of the lower sash 12, the said bracket being provided with a bearing at its upper extremity, in which is journaled a projecting stud or pin 15 fixed to one side of a cam 16. In contact with the periphery of the cam 16 is a bearing-plate 17 of spring metal which is also preferably secured to the 50 top edge of the lower sash adjacent to the parting bead 13. Between the bearing-plate 17 and the adjacent parting-bead 13

is a rod 18 which extends substantially the full length of the top sash, and is connected thereto at its extremities.

For operating the cam 16 I provide a 60 lever 19 which carries a lug 20 at a point intermediate its length, adapted to engage a notch in the periphery of the cam and a pin 21 secured at one end, which when the lever is in place, is received in an aperture 65 passing through the cam, as clearly shown in Fig. 4. By this construction the lever 19 may be readily displaced after the cam has been revolved to force the rod 17 into engagement with the parting bead, which will 70 prevent the window from being opened even though access to the lock be had. In this manner it will be impossible for a burglar to raise the sash after cutting the glass and passing his hand through the window to the 75 lock. It is thus seen that I have produced a very simple device which is capable of locking both sashes at any desired point within the window frame.

The sash lock as shown and described 80 while being my preferred form of construction, may nevertheless be modified without departing from the nature of the invention as defined within the scope of the annexed claims.

Having thus described my invention, I 85 claim as new and desire to secure by Letters Patent:

1. In combination with an upper and lower window sash separated by a parting bead, a sash lock comprising a bracket secured to the top of the lower sash, a cam journaled on the bracket, a rod attached to the upper sash between the cam and parting bead, a binding-plate carried by the lower 95 sash and interposed between the rod and cam, and a lever for operating the cam to bind said rod against the parting bead.

2. In combination with a window frame having sashes slidable therein, a device carried by one of said sashes, and means carried by the other sash for binding said device against said frame, whereby both of said sashes are frictionally locked within the 100 frame.

3. In combination with a frame having sashes slidable therein, a cam carried by one sash, means carried by the other sash arranged between the cam and window frame, and means for revolving the cam to bind 110 said first-named means to the frame and lock both of said sashes.

4. In combination with a frame having sashes slideable therein, a cam carried by one sash, means carried by the other sash arranged between the cam and window frame, 5 and a lever detachably connected to the cam for revolving it to bind said means to the frame and lock both of said sashes.
5. In combination with a frame having sashes slideable therein, a cam carried by one 10 sash, a rod carried by the other sash between

the cam and frame, and displaceable means for operating the cam to bind said rod against the frame for the purpose described.

In testimony whereof I have signed my name to this specification in the presence of 15 two subscribing witnesses.

JESSE H. BARTON.
